UNITED STATES PATENT OFFICE

OZEMA WATSON, OF DALLAS, TEXAS

STRINGED MUSICAL INSTRUMENT

Application filed November 2, 1929, Serial No. 404,361. Renewed August 10, 1931.

This invention relates to the class of musical instruments, more particularly stringed instruments.

The primary object of the present invention is to provide a stringed instrument having a plurality of faces over each of which a group of strings is drawn, each group being tuned to a different key so that instead of the player having to readjust the tension of the strings to obtain the desired key it is only necessary to turn the body of the instrument to bring into playing position the group of strings tuned to the key desired.

The invention broadly contemplates the provision of an elongated rectangular hollow body in each of the four walls of which is formed a circular opening over which the strings of the instrument pass. Each face of the body has extending longitudinally thereof four strings which are held in a suitable rack or frame at one end and are connected to tightening keys at the other end so that the tension of the strings may be regulated as desired. With the four sets of strings adjusted or tensioned to sound in different keys four different keys may be played without changing the adjustment of the strings as is the usual practice with other stringed instruments.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a side elevational view of the instrument embodying the present invention.

Figure 2 is an enlarged central longitudinal section of the instrument.

Figure 3 is a detailed sectional view taken on the line 3—3 of Figure 2.

Referring more particularly to the drawings wherein like numerals of reference in-

dicate corresponding parts throughout the several views, the numeral 1 indicates generally the body of the instrument which, as shown, comprises the four elongated walls 2 connected at the ends by the square end walls 3 and 3' which thus give to the device a square cross-sectional contour.

One of the four side walls has formed therethrough intermediate its ends a sound opening 5 which opening is preferably circular as shown.

Upon the end wall 3 preferably at the central part thereof there is secured a handle 6 and along each of the four edges of this wall there is secured a plate 7 which is provided with four string receiving slots 8. At each end of the instrument each of the four walls 2 has arranged transversely thereof a bridge piece 9 over which extends the strings 10 each of which has one end knotted and engaged in a slot 8 of an adjacent plate 7.

The wall 3' is, as shown, relatively thick and it has formed therethrough along each of the four sides four string key receiving openings 11 in each of which openings is fitted a key 12 which comprises a shank 13 which positions in the opening and a head 14. That portion of the shank 13 which engages in an opening 11 is grooved or otherwise suitably roughened so that it will be held against rotation when turned to tighten up a string attached thereto. Between the grooved or roughened part of the shank and the head each key has an opening 15 therethrough in which an end of a string is engaged so that it will not slip from position when the string is wound thereon.

From the foregoing it will be seen that the strings upon each of the four sides of the instrument are drawn taught between the bridge pieces 9 by turning the keys 12, the loosening of the keys being prevented after the keys have been tightened to the proper degree by the frictional engagement of the roughened shanks thereof with the walls of the grooves in which they are located.

In order to assist the user in proper manipulation of the instrument each of the four walls may be marked to indicate the key to which the strings are tuned as for example

the strings extending over the wall having the opening 5 therethrough may be tuned to G, the other strings being tuned to C, D and F.

5 While the keys 12 may, of course, be formed of wood I prefer to form them of metal as longer life will be obtained from the instrument and replacement of keys will be unnecessary whereas wooden keys will be 10 come broken and require replacement.

Having thus described my invention, what I claim is:—

1. A stringed musical instrument comprising an elongated hollow body of polygonal 15 cross-sectional design, one of the side walls of said body having a sound opening formed therethrough, end walls in the body, a slotted plate extending along each edge of one end wall, strings extending longitudinally over 20 each of said side walls and each having one end attached to an adjacent slotted plate, a bridge extending transversely of each side wall for the support of the strings passing thereover, and means for tensioning said 25 strings from the other ends thereof.

2. A stringed musical instrument comprising an elongated hollow body of polygonal cross-sectional design, one of the side walls of said body having a sound opening formed 30 therethrough, end walls in the body, a slotted plate extending along each edge of one end wall, strings extending longitudinally over 35 each of said side walls and each having one end attached to an adjacent slotted plate, a bridge extending transversely of each side wall for the support of the strings passing thereover, means for tensioning said strings from the other ends thereof, and a handle 40 secured to one of said end walls.

40 3. A stringed musical instrument comprising an elongated hollow body of polygonal cross-sectional design, one of the side walls of said body having a sound opening formed therethrough, end walls in the body, a slotted 45 plate extending along each edge of one end wall, bridge pieces extending transversely of each side wall at each end of the same, strings overlying each of said side walls and each connected at one end with said slotted plate 50 and extending across the bridges of the adjacent wall, and means in the other end wall having said strings connected thereto and by which the same may be tensioned to a desired key.

55 4. A stringed musical instrument, comprising an elongated body of polygonal cross-section having transverse head and base walls and side walls, said body having one of the side walls provided with an opening, a plurality of strings extending longitudinally of the face of each side wall and secured at one end thereto, bridges supporting said strings at each end of the instrument, and key members rotatably mounted in 60 the base wall and each having the other end

of a string secured thereto, said keys extending substantially longitudinally of the instrument.

In testimony whereof I hereunto affix my signature.

OZEMA WATSON.
